ABRASIVE TOOL

Robert Ellis, York, Pa.

Application January 22, 1944, Serial No. 519,269

3 Claims. (Cl. 51—205)

This invention relates to abrasive tools and the object of the invention is the provision of an abrasive tool in any of the many commercial forms such as hones, knife sharpeners, etc., which will have magnetic properties.

A further object of the invention is the provision of an abrasive instrument or tool in which the core may be of magnetic material and permanently magnetized and the outer shell of the tool of any desired abrasive constituency.

Other and further objects will appear in the specifications and be specifically pointed out in the appended claims, reference being had to the accompanying drawing exemplifying the invention and in which;

Fig. 1 is an isometric view of one form of my invention in the shape of a hone.

Fig. 2 illustrates another form of my abrasive tool in the shape of a knife sharpener, shown in longitudinal section.

Fig. 3 is a cross-section on the line 3—3 of Fig. 2.

Fig. 4 illustrates a microscopic view of the edge of a knife and how my magnetic abrasive tool will produce a sharper edge than an ordinary abrasive tool.

Referring to the drawing in which like numerals and characters of reference refer to similar parts throughout the several views, the numeral 5 denotes an ordinary abrasive hone in shape. The ingredients of the abrasive hone may also contain any of the numerous and varied mixtures of abrasive and binder therefor. However, in my abrasive hone I also include to any of the many compositions above referred to, a quantity of magnetic material such as powdered steel, powdered "alnico" or any of the few additional magnetic elements or alloys now generally employed in the manufacture of permanent magnets. The relative quantity of this powdered or granulated magnetic ingredient, added to the abrasive and binder of the hone may be approximately ten to ninety per cent, depending to what particular use the hone or abrasive tool is to be put to. The hone may also constitute a bar of steel set with abrasive diamonds or diamond dust, the steel bar being then magnetized, as in Fig. 1.

In the drawing, the abrasive particles such as carborundum, emery, etc., may be indicated by the numeral 6 and the magnetic particles by 7 although in use, the relative size of both ingredients would be a matter conditioned by the particular requirements. In making this abrasive hone or tool, the ingredients as mentioned above are first compounded in the proper proportion with

a binder, poured or compressed in a mold and when in solid or semi-plastic condition are permanently magnetized by momentarily being thrust within a strong magnetic field produced by direct electric current. The abrasive tool thereby becomes residually magnetized and is to all intents and purposes a permanent magnet, the letter N denoting the north magnetic pole and the letter S the south pole.

10 In use, attention is drawn to Fig. 4 which simulates a microscopic view of the edge of a knife 10, there being always "ribbons" 8 projecting at angles from the center line of the knife blade. An ordinary abrasive hone can never prevent these

15 microscopic ribbons and shreds from forming as they are too thin to be abraded, simply bending over when the hone presses thereon. With my magnetic hone however, these thin ribbons are attracted to the hone and the magnetic attraction

20 between the hone and the ribbons provide the proper friction, regardless of how thin or flexible the ribbons are, for abrasive action and these ribbons are thus abraded away or sharpened, leaving a sharper and clearer edge to the knife

25 than was heretofore possible, the resultant edge being denoted by the numeral 9. Furthermore, in any honing or abrading operation, it has heretofore always been necessary to apply pressure against the surface of the article being abraded as well as longitudinal motion. With the use of

30 my magnetic abrasive tool, the mutual magnetic attraction between the tool and the ferrous article eliminates the necessity of this pressure and only longitudinal motion is required, thus making the act of sharpening much easier. An additional advantage is that heretofore the fine particles of steel which were abraded from the knife

35 were either scattered around as dust or clung to the knife, later to contaminate food which was cut with the knife. During the sharpening process with my magnetic hone, such abraded steel particles will forcibly cling to the hone by magnetic attraction where they can later be wiped off with a cloth. A still further advantage of my

40 magnetic abrasive tool is the fact that a sharper edge can be given to the knife 10 by passing the hone 5 thereover, in the direction of arrow 11, by holding the hone at only a very slight angle, as

45 illustrated, from the face of the blade, the usual practice having heretofore been to hold the hone at a greater angle which resulted in a more stubby edge and ribbons as heretofore explained.

In Figs. 2 and 3 are illustrated a modification of my magnetic hone. In this arrangement, the

50 steel core 12 may be permanently magnetized and

the abrasive material 6 molded around this core. The abrasive shell should be thin enough to permit the magnetism inherent in core 12 to be effective on the article to be sharpened. The numeral 13 represents a handle which is fastened to the magnetic steel core 12 by means of screw 14. A number of annular grooves 15 are provided in the magnetic core 12 so that the abrasive shell may better adhere thereto.

From the foregoing description it will be apparent that I have evolved an abrasive tool with novel properties so that a knife or other edge may be given a sharper edge, one which will require less physical effort to operate and one which will prevent the usual abraded steel dust from flying about. Various changes may be made in the embodiment of the invention hereinabove specifically described without departing from or sacrificing the advantages of the invention as defined in the appended claims.

I claim:

1. The process of making an abrasive tool which consists of the following steps; first mixing magnetizable material with powdered or granulated abrasive material and a binder; second, molding or pressing said mixed material into a solid mass;

5 and third, inserting the solidified article into a magnetic field generated by direct electric current so that it will retain its magnetism permanently.

2. The process of making an abrasive tool which consists of the following steps; first, mixing powdered or granulated magnetizable material with powdered or granulated abrasive material and a binder; second, pouring or pressing said mixed material into a mold; third, inserting the plastic or semi-plastic material within said mold into a magnetic field generated by direct electric current so that the said magnetizable particles in said mold will arrange themselves in magnetically favorable positions in alignment with the magnetic lines of force of said magnetizing field and becoming permanently magnetized; and fourth, permitting said plastic or semi-plastic material in said mold to harden.

20 3. An abrasive tool comprising a mixture of magnetizable particles and abrasives in powdered or granulated form, and a binder for said particles, said tool being permanently magnetized to form an individual magnet with oppositely disposed magnetic poles.

25 ROBERT ELLIS.
